US00D781273S

(12) **United States Design Patent** (10) Patent No.: **US D781,273 S**
(45) Date of Patent: **** Mar. 14, 2017**

(54) **NETWORK HUB**

(71) Applicant: **Samsung Electronics Co., Ltd.**

Suwon-si (KR)

(72) Inventors: **Howard Nuk**, San Francisco, CA (US);
Jinseok Hwang, Walnut Creek, CA (US); **Alex Millie**, San Francisco, CA (US); **Seounghyun Son**, San Francisco, CA (US); **Jeffrey Jones**, San Francisco, CA (US); **Jiyeon Lee**, Emeryville, CA (US); **Jeremy David Baker**, Richmond, CA (US)

(73) Assignee: **SAMSUNG ELECTRONICS CO., LTD.**, Suwon-si (KR)

(**) Term: **15 Years**

(21) Appl. No.: **29/544,090**

(22) Filed: **Oct. 30, 2015**

(51) LOC (10) Cl. **14-03**

(57) **CLAIM**

The ornamental design for a network hub, as shown and described.

DESCRIPTION

FIG. 1 is a front perspective view of a network hub showing our new design;

FIG. 2 is a front elevation view thereof;

FIG. 3 is a rear elevation view thereof;

FIG. 4 is a left-side elevation view thereof;

FIG. 5 is a right-side elevation view thereof;

FIG. 6 is a top plan view thereof; and,

FIG. 7 is a bottom plan view thereof.

The broken lines in the figures illustrate portions of the network hub that form no part of the claimed design.

1 Claim, 7 Drawing Sheets
